UNITED STATES PATENT OFFICE.

CHARLES S. STANTON, OF COOPERSTOWN, NEW YORK.

AUTOMATIC RAILWAY-CONTROL SYSTEM.

1,084,047.

Specification of Letters Patent.

Patented Jan. 13, 1914.

Application filed June 8, 1913. Serial No. 772,472.

To all whom it may concern:

Be it known that I, CHARLES S. STANTON, a citizen of the United States, residing in Cooperstown, Otsego county, State of New York, have invented certain new and useful Improvements in Automatic Railway-Control Systems, of which the following is a specification.

My invention relates to means for automatically bringing to a stop a railway car or train, whether operated by electricity or other motive power when it passes a block signal set against it.

My improved system acts upon the brakes and motive power of the car or train independently of the motorman's or engine-driver's control system, and is in turn operated by the block signal system. The mechanism is such that it may be readily installed in existing motive power and signal systems.

In the accompanying drawings which form a part of this specification, Figure 1 is a diagrammatic view of my improved device as applied to an electrically operated car, in which the current for operating the stop system is furnished by a rotary converter or motor generator set energized by the main current; Fig. 2 is a similar diagrammatic view in which the power for operating the stop system is derived directly from the main current; Fig. 3 is a diagrammatic view of the device as applied to a steam or other fluid-operated locomotive; Fig. 4 is a longitudinal sectional view of the main valve mechanism; Fig. 5 is a similar view taken on a plane at right angles to that of Fig. 4, and Fig. 6 is a transverse sectional view on line VI—VI of Fig. 4.

Referring to the drawings in detail, and particularly to Fig. 1, the numeral 1 designates the frame of a car running on the tracks 2 and deriving its power through a trolley 3 contacting with the trolley wire 4, connected to one side of the dynamo 5, the other side of which is grounded to the track through the wire 6. Current is led down from the trolley through the lightning arrester 7 and wire 8 to the fluid-operated circuit breaker 9, thence through wires 10, 11 and 12 to the main motors 13 and 14 which are provided with appropriate controllers 15 and 16, respectively. The motors are, of course, grounded through the trucks and

wheels to the rails in the usual manner, although for the sake of clearness this connection is not shown. The motor generator or rotary converter 17 is operated by current from the main circuit through wires 18 and 19, the latter being grounded through the truck. This rotary converter or motor generator feeds a secondary circuit comprising wire 22, contact shoe 23, which is normally insulated from the truck frame, wire 24, solenoid 25, and wire 26. It will be observed that this circuit is completed only when the contact shoe engages the third rail 27, when the latter is grounded through wire 28, switch 29 and wire 30 connected to the track. The switch 29 is adapted to be operated by the same mechanism which controls the signal 31. When the signal is in the danger position shown in the full lines in Fig. 1, the switch will be closed and the rail 27 grounded. When the block ahead is clear, the signal will assume the dotted position, the third rail 27 will be insulated and the passage over it of the shoe 23 will not energize the solenoid 25. In case the signal is set at danger the secondary circuit of the rotary converter or motor generator will be completed through the contact shoe, third rail and track, causing current to pass through the solenoid and drawing upward its armature 32. The raising of the armature 32 will lift the stem 33, the lower end of which, 34, normally closes a port 35 in the valve mechanism which controls the supply of compressed air to the various actuating means. The opening of this port permits compressed air from the storage tank 36, fed by the compressor 37, to pass through the main supply-pipe 38 and by-pass 39 into the chamber 40, and thence through the port 35 into the top of the cylinder 41. The admission of the air into the cylinder will depress the piston 42 mounted on the piston rod 43 and normally forced into the top of the cylinder by means of the spring 44. The piston rod passes through a stuffing box 45 and carries at its lower end the valve 46 controlling admission to the port 47. When air is admitted into the upper end of the cylinder 41, the piston is forced downward into the position shown in Fig. 5, resulting in the opening of the port 47, which permits the compressed air entering the chamber 48 through the pipes 39 and 49 to pass

upward through the port 47 into the chamber 50, and thence out through the diverging pipes 51, 52 and 53. The pipe 52 leads to the compressed air whistle 54 situated in 5 any suitable position to give the engine-driver or motorman warning. The pipe 51 leads to the fluid-controlled circuit breaker 9 in the main motor circuit, while the pipe 53 communicates with a special valve 54. 10 The passage of compressed air through this pipe lifts the valve from its seat and the air rushes through the pipe 55 to the air brake mechanism 56. The lifting of the valve 54 automatically prevents the release 15 of the air through the engineer's valve 57 and vent 58. The result of the energizing of the secondary circuit of the motor generator or rotary converter is thus threefold: first, to sound an alarm; second, to break the 20 main motor circuit; and third, to apply the brakes. After the car or train has been brought to a stop, the engine driver or motorman may resume control of the mechanism by pressing the button 59, thus opening 25 the valve 60 and permitting the compressed air above the piston to escape through the ports 61 and 62. The spring 44 will then cause the piston to assume its upper position, shown in Fig. 4, and to close the valve 30 46. This action will be possible because the length of the third rail 27 is less than the distance in which the train will be brought to a stop by the action of the stop mechanism. This rail need only be long enough 35 to insure the positive operation of the solenoid, since when the piston 42 is once forced downward by the compressed air, the closing of the valve 34 can do no harm, as the air is entrapped above the piston until the relief 40 valve 60 is operated. The compressed air in the chamber 50 and the pipes 51, 52 and 53 leading therefrom will soon exhaust through the whistle 54, with the result that the circuit breaker 9 will close the main circuit 45 and the brakes will be released, all the parts returning to their original position, as shown in Fig. 1.

In Fig. 2 I have shown a modification, the 50 operation of which is similar in all respects to that of the type of mechanism hitherto described, with the exception that the current for operating the device is derived directly from the main circuit through a resistance 63, instead of from the motor generator or rotary converter set shown in Fig. 1. Fig. 2 shows the parts in the positions they will assume when the operating circuit 60 is closed, the circuit breaker being opened and the special valve 54 lifted to its upper position to close the vent 58 and afford passage for the compressed air from the storage tank into the brake line.

In Fig. 3 I have shown a further modification in which the stop device is applied 65 to a locomotive operated by steam or other

fluid pressure. In this type the operating circuit comprises wire 64 grounded at one end to the truck or car frame, battery 65, or other suitable source of current supply carried by the car or train, such as a small generator with a storage battery floating on the line, wire 66, solenoid 25, wire 67, and contact shoe insulated from the car frame or truck. The main compressed air valve mechanism is similar to that shown in Figs. 4 and 5 and has the three discharge pipes 68, 69 and 70. The pipe 68 leads to the whistle 71, while the pipe 69 is connected to a fluid operated valve 72 interposed in the main steam line 73, the valve being arranged to close when air is admitted to it. The third pipe 70 leads to a fluid-pressure-operated valve 74 having the two ports 75 and 76. When the parts are in their normal position, the spring 77 forces the piston 78 upward, as shown in Fig. 3, closing the port 75 and opening the port 76, thus permitting the brake line 79 to communicate with the vent 80 through the engineer's train valve 81. When compressed air is admitted to the discharge pipes 68, 69 and 70 in the manner already described, the whistle will be sounded, the main steam line closed, and the piston 78 forced downward, closing the port 76 and opening the port 75, thereby admitting compressed air from the tank 56 into the brake line 79 through the pipes 78 and 82, and thus applying the brakes to the car or train. The result of the contacting of the shoe 23 with the third rail when the signal is set at danger will, as before, be three-fold; to sound a warning, to shut off the motive power of the car or train, and to apply the brakes. The release of the stop mechanism may be effected as in the type 105 already described by pressing the button 59 of the relief valve 60.

It is to be understood that the mechanism shown in Figs. 1, 2 and 3 is largely diagrammatic and that any suitable type of valve or circuit breaker may be employed in place of the mechanism diagrammatically shown.

While I have illustrated and described only certain preferred embodiments of my device, I realize that my invention is susceptible of broad application, and I do not desire to be limited to the exact structure shown and described.

Having thus described my invention, I claim:

1. A system of railway control comprising pressure-operated mechanism for cutting off motive power and applying a brake, and an alarm co-operating with said mechanism and operating to release the brake and restore 125 the motive power by exhausting said pressure.

2. A system of railway control comprising an air brake system, pressure-operated mechanism auxiliary to said air brake sys- 130.

tem for cutting off motive power and applying a brake, and an alarm coöperating with said mechanism and operating to release the brake and restore the motive power by exhausting said pressure.

3. A system of railway control comprising pressure-operated mechanism for cutting off motive power and applying a brake, an alarm coöperating with said mechanism and operating to release the brake and restore the motive power by exhausting said pressure, and means for controlling the operation of said mechanism.

4. A system of railway control comprising pressure-operated mechanism for cutting off motive power and actuating a brake, and an alarm coöperating with said pressure-operated mechanism and operating to exhaust said pressure whereby said brake may be released and said motive power restored.

5. A system of railway control comprising pressure-operated mechanism for cutting off motive power and actuating a brake, an alarm coöperating with said pressure-operated mechanism and operating to release the brake and restore the motive power by exhausting said pressure, and means for controlling the operation of said mechanism.

6. A system of railway control comprising pressure-operating mechanism for cutting off the motive power and applying a brake, an alarm coöperating with said mechanism and operating to release the brake and restore the motive power by exhausting said pressure, and electrically operated signal controlled means for controlling the operation of said mechanism.

7. A system of railway control comprising an air brake system, mechanism utilizing pressure in said air brake system for cutting off motive power and applying a brake, an alarm coöperating with said mechanism and operating to release the brake and restore the motive power by exhausting said pressure, and electrically operated signal controlled means for controlling the admission of pressure from said air brake system into said mechanism.

8. A system of railway control comprising an air brake system, pressure operated mechanism for cutting off motive power and applying a brake, a valve for controlling admission of pressure from said air brake system into said mechanism, and an alarm coöperating with said mechanism and operating to release the brake and restore the motive power by exhausting said pressure.

9. A system of railway control comprising an air brake system, pressure-operated mechanism for cutting off motive power and applying a brake, a valve for controlling admission of pressure from said air brake system into said mechanism, an alarm coöper-

ating with said mechanism and operating to release the brake and restore the motive power by exhausting said pressure, and means controlled exterior to a railway vehicle for operating said valve.

10. A system of railway control comprising an air brake system, pressure-operated mechanism for cutting off motive power and applying a brake, a valve for controlling admission of pressure from said air brake system into said mechanism, an alarm coöperating with said mechanism and operating to release the brake and restore the motive power by exhausting said pressure, and electrically operated signal controlled means for operating said valve.

11. A system of railway control comprising an air brake system, mechanism utilizing pressure in said air brake system for cutting off motive power, applying a brake and operating an alarm, said alarm being adapted to exhaust the pressure in said mechanism whereby said brake is released and said motive power restored, and an electrically controlled valve device for connecting and disconnecting said mechanism with said air brake system.

12. A system of railway control comprising an air brake system, mechanism utilizing pressure in said air brake system for cutting off motive power, applying a brake and operating an alarm, said alarm being adapted to exhaust the pressure in said mechanism whereby said brake is released and said motive power restored, and means for connecting and disconnecting said mechanism with said air brake system.

13. A system of railway control comprising an air brake system, a valve adapted to be operated by pressure in said air brake system for opening a series of ports leading to a motor cut-off, a brake, and an alarm, said alarm being adapted to exhaust said pressure whereby said brake is released and said motive power restored, and an electrically controlled valve device for controlling the opening and closing of said valve.

14. A system of railway control comprising an air brake system, a valve adapted to be operated by pressure in said air brake system for opening a series of ports leading to a motor cut-off, a brake, and an alarm, said alarm being adapted to exhaust said pressure whereby said brake is released and said motive power restored, and means for controlling the opening and closing of said valve.

15. A system of railway control comprising an air brake system, a valve adapted to be operated by pressure in said air brake system for opening a series of ports leading to a motor cut-off, a brake, and an alarm, said alarm being adapted to exhaust said pressure whereby said brake is released and said motive power restored, and means

adapted to be operated by the closing of an electric circuit for controlling the opening and closing of said valve.

16. A system of railway control comprising an air brake system, a valve casing having a series of connections with a motor cut-off, a brake, and an alarm, a connection with said valve casing and said air brake system, a valve controlling the admission of pressure from said air brake system to said casing, a piston operated by pressure from the air brake system to open and close said valve, and an electrically operated valve device for controlling the operation of said piston.

17. A system of railway control comprising an air brake system, a valve casing having a series of connections with a motor cut-off and a brake, a connection with said valve casing and said air brake system, a valve controlling the admission of pressure to said casing, a piston operated by pressure from the air brake system to open and close said valve, an electrically operated valve device

for controlling the operation of said piston, 25 and an alarm coöperating with said valve casing and adapted to exhaust the pressure therein whereby said motive power may be restored and said brake released.

18. A system of railway control comprising an air brake system, a valve casing having a series of connections with a motor cut-off and a brake, a connection with said valve casing and said air brake system, a valve controlling the admission of pressure to said 30 casing, a piston operated by pressure from the air brake system to open and close said valve, an electrically operated signal controlled valve device for controlling the operation of said piston, and an alarm coöperating with said valve casing and adapted to 35 exhaust the pressure therein whereby said motive power may be restored and said brake released.
